COMBINATION UMBRELLA STAND AND
RUBBERS UTILITIES CABINET

Henry Cohen, New York, N. Y.

Application December 27, 1938, Serial No. 247,810

5 Claims. (Cl. 312—149)

This invention relates to new and useful improvements in a combination umbrella stand and rubbers utility cabinet.

More specifically, the invention proposes the construction of a combination umbrella stand and rubbers utility cabinet characterized by the provision of a hollow body open at its front and within which a plurality of trays are mounted in a particular manner for holding rubbers and for collecting the water which drips therefrom.

Another object of this invention is the provision of a shoe shine kit mounted in the bottom portion of said body in a manner to be removed therefrom to permit the kit to be used for shining shoes.

Still further the invention proposes the construction of hollow members formed upon the sides of said body and open at their tops in a manner to receive umbrellas.

Another object of this invention is the provision of trays mounted in the bottom of said hollow members and into which the bottom ends of the umbrellas are adapted to extend in a manner to permit the trays to collect the water which drips from the umbrellas.

Still further the invention proposes the construction of openings formed in the back of said members, or in the sides of said members, to permit said trays to be removed therefrom for emptying the water which collects therein.

Still further the invention proposes a new and novel manner for locking the trays in position within said members while umbrellas are located therein for preventing the removal of said trays until such time as the umbrellas are removed from said members.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a combination umbrella stand and rubbers utility cabinet constructed according to this invention.

Fig. 2 is a vertical sectional view on the line 2—2 of Fig. 1.

Fig. 3 is an enlarged detailed view of a portion of Fig. 2.

Fig. 4 is a vertical sectional view on the line 4—4 of Fig. 2.

Fig. 5 is a perspective view of one of the trays per se.

Fig. 6 is an enlarged detailed view of a portion of Fig. 2.

Fig. 7 is a rear perspective view of the combination umbrella stand and rubbers utility cabinet.

Fig. 8 is a sectional view on the line 8—8 of Fig. 7.

Fig. 9 is a view similar to Fig. 6 but illustrating a modification of the invention.

Fig. 10 is still another view similar to Fig. 6 and illustrating a further modification of the invention.

Fig. 11 is a perspective view of the shoe shine kit per se.

Fig. 12 is a view similar to Fig. 11 illustrating a different position of the parts.

Fig. 13 is a vertical sectional view on the line 13—13 of Fig. 12.

Fig. 14 is a perspective view of another umbrella tray constructed according to this invention.

Fig. 15 is a vertical sectional view taken on the line 15—15 of Fig. 14.

The combination umbrella stand and rubbers utility cabinet, according to this invention, includes a hollow body 10 having an open front side which is adapted to receive a plurality of trays 11 for holding rubbers. The sides of the hollow body 10 are formed with grooves 10 into which the edges of the trays 11 are adapted to be engaged for holding the trays in spaced superimposed positions within the body 10. The trays 11 are constructed of sheet metal or other similar material and are formed with upwardly extending flanges 11a for catching and collecting the water which drops from the rubbers placed therein. A lining pad of any suitable material may be placed in the trays 11. The position of the rubbers on the trays 11 is illustrated by the dotted lines 12 in Fig. 4. A plurality of vent openings 10' are shown in the rear wall of the hollow body 10.

A shoe shine kit is mounted within the bottom portion of the hollow body 10 beneath the lowermost tray 11 and rests on the bottom wall thereof. The shoe shine kit comprises a container 13 having an intermediate partition 13a dividing the same into separate compartments. The compartment on one side of the partition 13a is open and is adapted to receive the polish and other materials needed for shining shoes.

The compartment on the other side of the partition 13a has its top closed by means of a wall 13b. The adjacent end wall 13c of the container 13 is pivotally supported upon the wall 55

13b by means of a pair of hinges 14 and is adapted to be swung to a superimposed position upon the wall 13b. A shoe rest 15 is mounted upon the wall 13c and is adapted to be exposed when the wall 13c is in position on the wall 13b and is normally disposed within the compartment formed on one side of the partition 13a when the wall 13c extends vertically along the back of the container 13. The several adjusted positions of the wall 13c and the shoe rest are illustrated in Fig. 13.

When the shoe shine kit is to be used it is removed from the hollow body 10 and the wall 13c is pivoted to expose the shoe rest 15 to permit one's shoes to be rested thereon while being shined. When it is desired to again place the kit within the hollow body 10 the wall 13c is pivoted back to its normal position to permit the kit to be engaged in position between the bottom wall of the hollow body 10 and the lowermost tray 11.

A door 16 is provided for closing the open side of the hollow body 10 and is pivotally supported by means of hinges 17. A bolt 18 is mounted on the free edge of the door 16 and is adapted to engage a keeper 19 mounted upon a portion of the hollow body 10 in the closed position of the door for maintaining the same in its closed position.

Hollow members 20 are mounted upon the sides of the hollow body 10 and are open at their tops for receiving umbrellas 21. The regulation size men's umbrellas as well as the usual smaller size of ladies' umbrellas are readily accessible at the inclined upper openings of the hollow members 20.

Each of the hollow members 20 is characterized by a shelf 22 which is vertically resiliently supported in the bottom portion of the hollow member 20. The shelf 22 is resiliently supported by means of a plurality of springs 23a disposed between the bottom face of the shelf 22 and the top face of the bottom wall of the hollow member 20. A tray 23 for receiving the bottom ends of the umbrellas 21 is located within the hollow member 20 and normally rests upon the shelf 22. The tray 23 is designed for receiving the water which drips from the umbrellas. Pins 24 project from the sides of the tray 23 and are engageable into notches formed in bars 25 mounted upon the sides of the hollow member 20. The back wall of the hollow member 20 is formed with an opening 20a through which the tray 23 is adapted to be removed when the pins 24 are disengaged from the notched bars 25 to permit the water collected therein to be spilled therefrom.

When the umbrellas 21 are in position with their bottom ends engaging the horizontal wall of the tray 23 the weight of the umbrellas will force the shelf 22 downwards against the holding action of the springs 23a to engage the pins 24 into the notches formed in the bars 25 to prevent the tray from being removed through the opening 20a until such time as the umbrellas 21 are removed from the hollow member 20.

According to the modification of the invention shown in Fig. 9 the sides of the hollow body 10 are formed with a plurality of spaced molding strips 10b upon which the trays 11 are rested for supporting the same in superimposed positions within the body 10. In other respects this form of the invention is similar to the previous form.

According to the modification of the invention shown in Fig. 10 the hollow body 10 is formed with a plurality of grooves 10 in excess of the

number of trays 11 for permitting the trays to be supported in various superimposed positions with relation to each other. In other respects this form of the invention is similar to the previous forms.

According to the modification of the invention shown in Figs. 14 and 15, a perforated plate 23 or grille is placed in the tray and spaced above the horizontal wall of the tray 23; to permit the water from the wet umbrellas to stay in the tray below the fabric of the umbrella.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a device of the class described, a hollow member open at the top for receiving umbrellas, a shelf in the bottom portion of said member, means for resiliently supporting said shelf, a tray for receiving the bottom ends of umbrellas placed in said member and rested on said shelf, pins projecting from the sides of said tray, notched bars mounted on said member and engageable by said pins for holding the tray from being removed through an opening in said hollow member when an umbrella rests in said tray and its weight depresses said shelf.

2. In a device of the class described, a hollow member open at the top for receiving umbrellas, a shelf resiliently supported in the bottom portion of said member, a tray for receiving the bottom ends of umbrellas placed in said member and rested on said shelf, pins projecting from the sides of said tray, notched bars mounted on said member and engageable by said pins for holding the tray from being removed through an opening in said hollow member when an umbrella rests in said tray and its weight depresses said shelf, said resilient supporting of said shelf comprising springs operating between the bottom face of said shelf and the top face of the bottom wall of said hollow member.

3. In a device of the class described, a hollow member open at the top for receiving umbrellas, a shelf resiliently supported in the bottom portion of said member, a tray for receiving the bottom ends of umbrellas placed in said member and rested on said shelf, pins projecting from the sides of said tray, notched bars mounted on said member and engageable by said pins for holding the tray from being removed through an opening in said hollow member when an umbrella rests in said tray and its weight depresses said shelf, said opening being formed in the back wall of said hollow member and said tray being removable therefrom only when said umbrellas are removed from said members to permit said resilient means to disengage said pins from said notched bars and free said tray.

4. In a device of the class described, a hollow member having an open top and an end opening, a shelf mounted in the bottom of said member, springs resiliently supporting said shelf, a tray resting on said shelf and removable through said end opening and adapted to receive articles passed through said open top, notched bars extending along the sides of said tray and mounted on the side walls of said hollow member, and pins extending from the sides of said tray and normally

spaced from the top edges of said bars, whereby the weight of an article placed on said tray through said open top will cause said shelf and tray to be depressed to engage said pins into the notches of said bars to lock said tray against being removed through said end opening unless said article is again removed from said tray.

5. In a device of the class described, a hollow member having an open top adapted to receive articles placed therein and a receptacle in the lower end of said hollow member adapted to receive the lower ends of said articles, said hollow

member having an opening through the lower portion of the side wall thereof through which said receptacle may be removed, means for supporting said receptacle in either of two vertical positions in accordance with the presence or absence, respectively, of articles whereby said receptacle may be depressed by the weight of the articles to prevent removal of said receptacle and means for preventing removal of said receptacle when said receptacle is in depressed position. 10

HENRY COHEN.
